CULVERT

Raymond T. Lane, Bath, N. Y.

Application August 12, 1932. Serial No. 628,597

2 Claims. (Cl. 137—75)

The present invention relates to a culvert and particularly to that class of the flexible type. For many years it has been conceded that a flexible type of culvert has many advantages over the rigid type of construction. By rigid, I mean cast iron, concrete and the like. These rigid type culverts are apt to be broken or destroyed by the shifting of soils, freezing of soils and water or the heavy load imposed by traffic.

10 The flexible type of culvert such as corrugated iron pipe cannot be damaged by freezing actions and due to its flexibility is able to withstand the shifting of soil and heavy traffic much better than the rigid type as it can change its shape and alignment without being broken. However, 15 it has been known for some time that the corrugated type of culvert, which depends almost entirely upon the earth surrounding it for strength, should have more inherent strength in order that it might better meet the conditions 20 of service.

It has been advanced by those concerned with corrugated metal pipes that the great flexibility of the culvert would permit the vertical diameters to shorten and the horizontal diameter to lengthen when heavy loads were imposed upon it, thereby increasing the pressure of the earth against the sides. This has been proven to be true, but in a great many instances pressure of 25 the earth at the sides cannot be found great enough to equal the top load and the results have in these instances been failures by collapse.

It is also true that the flexible type of culvert is designed to work under conditions of 30 service where the pressure at the sides is slightly greater than those at the top and bottom and under no conditions should it be called upon to act as a beam across unequal foundations where 35 the points of bearing cause the invert to collapse. It has been found necessary to tamp the back fills around the pipe very carefully and this together with the natural tendency of the pipe to deflect under heavy loads has been the method 40 of gaining additional strength.

45 My invention comprises a flexible type of culvert which does not depend for strength upon the pressure of the earth at the side. The sides of my culvert are held securely in place by heavy 50 cradle arms which in turn are securely fastened to a structural steel or iron shelf. By means of its action in building up supports from the earth beneath these shelves, as will hereinafter be more 55 fully described, the culvert, from a structural standpoint, is able to combat any conditions of

service even to acting as a beam across unequal foundations.

Other objects of the invention are to provide a culvert of this type which may be manufactured at a low cost, is simple in construction, 30 strong and durable, thoroughly efficient and reliable in use and otherwise well adapted to the purpose for which it is designed.

With the above and numerous other objects in view as will appear as the description proceeds, 35 the invention consists in certain novel features of construction, and in the combination and arrangement of parts as will be hereinafter more fully described and claimed.

In the drawings:

Figure 1 is a vertical longitudinal section through a culvert embodying the features of my invention.

Figure 2 is a vertical transverse section therethrough.

Figure 3 is a top plan view of the bottom section.

Figure 4 is a bottom plan view thereof.

Figure 5 is a fragmentary perspective view showing the bottom section with a structural 60 steel or iron shelf detached therefrom.

Figure 6 is a fragmentary perspective view of one of the cradle arms.

Referring to the drawings in detail it will be seen that the numeral 5 denotes a bottom semi-cylindrical section which may be of any desired thickness and numeral 6 denotes a top semi-cylindrical section. The thickness of the bottom section 5 may be less than the thickness of the top section 6 without substantially detracting from the strength of the structure as a whole. The top section is corrugated. Fastened to the outer side of the bottom section 5 are heavy cradle arms 7 of arcuate formation to conform to the curvature of the section 5 and preferably of T-shaped formation in cross section. The cradle arms 7 are preferably spaced about four feet apart and there being one at each end of the culvert or section thereof. The end cradle arms are preferably of L-shaped formation in cross section to facilitate connecting two or more lengths of culvert. The arms may be fastened in place by means of bolts 8 or any other suitable fastening means. The bottom section at its longitudinal edges is provided with a pair of outwardly directed longitudinal flanges 9 to which are fastened structural steel or iron shelves 10 of L-shaped formation in cross section. For some purposes, such as gutters, flumes, and the like, the bottom section comprising the section 5, the cradle arms 7, 105

and the flanges 9 may be used as such without the addition of the top section 6. However, for use as a culvert under roads, railroad embankments and the like where heavy loads are imposed on the culvert, it is necessary to add the top section 6, the longitudinal edges of which rest on the shelves 10 and are prevented from collapsing inwardly by bolt heads or other devices.

From the above description it will be apparent that unlike prior flexible type culverts my culvert does not depend for strength upon the pressure of earth at its sides. The heavy cradle arms 7 together with the shelves 10 prevent lengthening of the horizontal diameter of both the bottom and top sections when under load. The earth or other filling material beneath the shelves 10 is compacted in the following manner. The culvert, when placed in the trench, rests upon the cradle arms 7 the legs of which hold the bottom section 5 above the bottom of the trench thus leaving a space for the culvert to settle. The thickness and depth of these legs will depend upon the diameter of the culvert and the character of the soil beneath, the thickness being great enough to support the weight of the culvert and the depth being great enough to permit the filling material beneath the shelves 10 to be properly compacted. In making the fill the material is so placed as to leave the space beneath the bottom section 5 substantially free of filling material. As the weight of the filling material or live load comes upon the top of the culvert the legs of the cradle arms 7 are forced into the soil and the material beneath the shelves 10 is compacted. Since the depth of the legs is sufficient to enable the compacted material to support the entire load, the bottom section 5 is not forced to support an excessive amount of the load to which the culvert is subjected.

The present embodiment of the invention has been described in considerable detail merely for the purposes of exemplification since in actual

practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A culvert of the class described comprising a bottom section having outwardly extending flanges at its side edges a cradle member in which the bottom section rests and to which it is secured, the ends of said cradle members resting against the bottom faces of the flanges, an angle bar connected to the upper face of each flange by its horizontal flange, the vertical flange of each angle bar being arranged outwardly, and a top section having its edges resting on the angle bars, the vertical flanges preventing the edge portions of said top section from moving outwardly off the bars.

2. A culvert of the class described comprising a plurality of arcuate cradle members, a semi-cylindrical bottom section resting in the cradle members and secured thereto, said bottom section having outwardly extending flanges at its edges having portions resting on the ends of the cradle members, an angle-shaped bar having its horizontal flange resting on each flange of the bottom member, with its vertical flange extending upwardly from the outer edge of the horizontal flange, bolts passing through the horizontal flanges of the angle bars and thru the flanges of the bottom sections, and a top section of semi-cylindrical shape having its edges seated on the angle bars and located between the vertical flanges thereof and portions of the bolts.
